MOUNTING DEVICE FOR MACHINE GUNS

John C. Trotter, Buffalo, N. Y., assignor to Bell Aircraft Corporation, Buffalo, N. Y., a corporation of New York

Application November 24, 1939, Serial No. 305,979

8 Claims. (Cl. 89—37)

In general the present invention relates to machine guns and more specifically to a mount for twin machine guns which is provided with means for the disposal of the ejected cartridge cases and links. Although my invention is illustrated and described in connection with twin .30 caliber machine guns for use in aircraft, tanks and armored cars, or the like, it is of broader scope and can be used for other purposes and with any caliber gun.

Heretofore no practical devices have been employed to dispose of and collect the ejected cartridge cases and links for twin gun assemblies. Of course this is due to the limited space between the guns and the conventional collection media cannot be used to best advantage. With the link type of cartridge it is economical to maintain the ejected links in good condition so that they can be reused, and my device conveys the links to a suitable collecting device wherein they remain in good condition and can be reused.

An object of this invention is to provide a mount for twin machine guns, which also provides means for conveying the ejected links to a container or the like from which they can be collected for reuse.

Another object of my invention is to provide in a unitary structure a frame having means for the disposal of the ejected cases and links.

To achieve the above and other objects, my invention in general comprises a pair of light weight cradles supporting twin machine guns which are carried by a mount that is adapted to be swiveled in a socket in the aircraft or tank. The mount also has formed therewith a chute or the like which is in communication with the link ejector slots of the machine guns and into which the ejected links from both guns are adapted to fall. A container such as a bag is fitted around the lower open end of the chute for collecting the ejected links.

In the drawings in which like numerals designate the same or similar parts.

Figure 1 is a top plan view illustrating my invention.

Figure 2 is a view in side elevation of the device shown in Figure 1.

Figure 3 is a sectional view taken along the line 3—3 of Figure 1.

Figure 4 is a sectional view taken along the line 4—4 of Figure 3.

Figure 5 is a fragmental view in side elevation illustrating the ejection slot when the guns are elevated upwardly.

Figure 6 is a view similar to Figure 5 showing the position of the slot when the guns are moved downwardly.

Referring to Figures 1 and 2 of the drawings, it can be seen that my mounting means comprises a vertical support 1 having a pair of parallel light weight cradles 2 associated with its upper extremity. A machine gun 3 is carried by each of the cradles. In view of the fact that the construction and operation of the cradles, firing handles, recoil, absorbing units, etc., have been fully described and illustrated in my co-pending application, Serial No. 303,283, filed November 7, 1939, for "Mount for machine guns," I will not repeat the description in this application.

It can be seen from Figure 3 that the support 1 comprises a hollow drum 4 which is cut away at its upper portion as shown by the numeral 5. A bore 6 is provided in the drum and a pin 7 is rotatably mounted therein. Discs 8 are disposed on opposite sides of the drum 4 thus closing the cut-away portion 5, and being supported by the pin 7. A saddle 9 is attached to each end of the pin 7 as shown at 10 and each of the cradles 2 is suitably secured to its respective saddle as shown at 11. Since the cradles are attached to the pin 7, it is clear that they are rotatably mounted for vertical movement so that the guns 3 may be fired in an upward or downward direction.

Integrally formed with the drum and extending downwardly therefrom is a chute 12 that is provided with an offset discharge mouth 13. An extension 14 is integrally formed with the chute 12 and is provided with a vertical bore 15. The upper end of a spindle 16 is fitted into the bore 15 and the lower end of the spindle is positioned in a socket or the like to permit the support to have a swiveling movement.

As best shown in Figures 3 and 4 each disc 8 is formed with a slot that is elongated so that the cartridge links will be ejected at any recoil position of the guns. The slot 20 is adapted to be spaced from and in alignment with a link ejector slot 21 provided in the machine gun. It will be appreciated that the slots 20 and 21 will always be in alignment regardless of whether the guns are firing in a forward, upward, or downward direction.

Since the upper portion of the drum 4 is cut away as designated by the numeral 5, the links passing through the aperture 20 will of course be deposited in the drum 4 from whence they 55 will move into the chute 12. In general, the

cut-away portion 5 is of such size that the slot 20 will be in communication therewith for 70° movement of the guns either above or below the horizontal. Consequently, regardless of the direction in which the guns are firing, the ejected links will always pass into the chute 12 and a collecting device such as a bag can be attached to the mouth 13 of the chute for collecting the ejected links.

It is believed apparent from the above description of my invention that I have provided a highly effective means for collecting the cartridge links ejected by twin machine guns. The device is simple in construction, light in weight, and forms part of the framework for supporting the guns. By being positioned between the twin guns, it consumes very little space and additionally forms a portion of the mount for attaching the guns for swiveling the guns for swiveling movement in the airplane.

While I have shown and described the preferred embodiment of my invention, I wish it to be understood that I do not confine myself to the precise details of construction herein set forth by way of illustration, as it is apparent that many changes and variations may be made therein, by those skilled in the art, without departing from the spirit of the invention, or exceeding the scope of the appended claims.

I claim:

1. In a twin machine gun assembly for use in aircraft or the like, a support adapted to be swiveled in the aircraft, cradles for carrying the machine guns, the cradles being attached to the support on opposite sides thereof, said support having means for admitting cartridge links ejected from the machine guns into the support.

2. In a twin machine gun assembly for use in aircraft or the like, a hollow vertical support adapted to be swiveled in the aircraft, cradles for carrying the machine guns, the cradles being attached to the support on opposite sides thereof, said support having means for admitting cartridge links ejected from the machine guns into the support.

3. In a twin machine gun assembly for use in aircraft or the like, a vertical support adapted to be swiveled in the aircraft and provided with a downwardly extending chute, cradles for car-

rying the machine guns, the cradles being attached to the support on opposite sides thereof, said support having means to admit the cartridge links ejected from the machine guns into the chute.

4. In a twin machine gun assembly for use in aircraft or the like, a vertical support adapted to be swiveled in the aircraft and provided with an offset downwardly extending chute, cradles for supporting the machine guns attached to the upper end of the support on opposite sides thereof, and the upper portion of said support having a slot through which cartridge links ejected from the machine guns are adapted to pass.

5. In a machine gun assembly for use in aircraft, a hollow vertical support adapted to be swiveled at its lower extremity in the aircraft and provided with an offset downwardly extending chute, cradles for carrying the machine guns, said cradles being mounted on the support on opposite sides thereof, and the upper portion of the support having a slot through which the cartridge links ejected from the machine guns are adapted to pass.

6. A twin machine gun assembly for use in aircraft or the like, comprising a hollow vertical support adapted to be swivelled at its lower end in the aircraft and provided with an offset downwardly extending chute, and means forming cradles to mount the machine guns on the support, the upper end of the support having slots to admit cartridge links ejected from the machine guns into the downwardly extending chute.

7. A twin machine gun assembly, comprising a support constructed to receive cartridge cases and links, and cradles for carrying the machine guns attached to the support on opposite sides thereof, said support having slot means through which the links ejected from the machine guns are adapted to pass.

8. A twin machine gun assembly, comprising a support constructed to receive cartridge cases and links, and cradles for carrying the machine guns attached to the support on opposite sides thereof, the upper portion of the support having slots through which the cartridge links ejected from the machine guns are adapted to pass.

JOHN C. TROTTER.
